ROCKING CHAIR

Ralph Mondragon, P.O. Box 199, Ranchos de,
Taos, N. Mex. 87571

Filed Nov. 29, 1968, Ser. No. 14,713

Term of patent 14 years

Int. Cl. D6—01

U.S. CL. D15—6

FIG. 1 is a side elevational view of a rocking chair showing my design;

FIG. 2 is a top view of FIG. 1;

FIG. 3 is a front side view of FIG. 1; and

FIG. 4 is a back side view of FIG. 1.

The side of the rocking chair not shown is a mirror image of the side shown.

I claim:

The ornamental design for a rocking chair, as shown and described.
